CLAIM

The ornamental par lamp, as shown and described.

DESCRIPTION

FIG. 1 is a front, top perspective view of the new design for a lamp;

FIG. 2 is a top plan view thereof;

FIG. 3 is a rear perspective view as seen from the side thereof;

FIG. 4 is a side elevational view thereof;

FIG. 5 is a rear view thereof;

FIG. 6 is a front, top perspective view of a second embodiment of the design for a lamp;

FIG. 7 is a top plan view of the second embodiment;

FIG. 8 is a rear perspective view of the second embodiment as seen from the side;

FIG. 9 is a side elevational view of the second embodiment; and,

FIG. 10 is a rear view of the second embodiment.

The broken line disclosure is for environmental purposes only and does not form a part of the claimed design.
